UNITED STATES PATENT OFFICE.

GEORGE E. ROLLINS, OF BROCKTON, MASSACHUSETTS, ASSIGNOR OF ONE-HALF TO
JOHN R. McLAUGHLIN, OF HOLBROOK, MASSACHUSETTS.

BOOT OR SHOE STIFFENER.

1,184,661.

Specification of Letters Patent. Patented May 23, 1916.

Application filed August 12, 1914. Serial No. 856,467.

To all whom it may concern:

Be it known that I, GEORGE E. ROLLINS, a citizen of the United States, and a resident of Brockton, Plymouth county, Massachusetts, have invented an Improvement in Boot or Shoe Stiffeners, of which the following description, in connection with the accompanying drawings, is a specification, like characters on the drawings representing like parts.

This invention relates to stiffeners for boots and shoes, and is more particularly concerned with a novel heel counter or toe box, and method of making the same.

My invention will be best understood by reference to the following specification, when taken in connection with the accompanying drawing of one specific embodiment of a heel counter, and one of a toe box, while its scope will be more particularly pointed out in the appended claims.

In the drawings: Figure 1 is a side elevation of a heel counter embodying my invention; Fig. 2 is a bottom plan of the same; Fig. 3 is a sectional view on line 3—3 of Fig. 2; Fig. 4 is a side elevation of a toe box embodying my invention; Fig. 5 is a bottom plan of the same; Fig. 6 is a sectional view on line 6—6 of Fig. 5; Fig. 7 is a plan of a blank prepared according to the first step in the preferred method of making the heel counter; Fig. 8 is a sectional view on line 8—8 of Fig. 7; Fig. 9 is a sectional view similar to Fig. 8, but showing the stiffener having fixed thereto a reinforcing element; and Fig. 10 is a vertical cross-sectional view of the heel portion of a shoe having a heel counter embodying my invention.

Referring to the drawings, and first more particularly to Figs. 1, 2, 3, and 7 to 10, inclusive, which illustrate one form or embodiment of my invention, and the preferred method of making the same, I have there shown a heel counter having an upstanding flange 11 and an inwardly-turned flange 12, presenting at their juncture an angular outer corner 13, preferably substantially a right angle. It is desirable that the upstanding flange shall be relatively thick and stiff, in order to have the necessary stability to stiffen and strengthen the shoe about the heel portion of the same. Therefore, the upstanding flange is by preference made relatively thick and stiff, while the inwardly-turned flange is preferably rela-

tively thin and flexible up to a point contiguous to its juncture with the upstanding flange, whereby it forms at that point a species of hinge having capacity for flexing both before and after it is built into the boot or shoe. It will be observed, moreover, that the lower surface of this flange is substantially flush with the lower edge of the upstanding flange, and that it provides a flatter bottom surface than heel counters heretofore in use. Its use eliminates the cracking of the material incidental to bending the whole thickness of the blank, and insures permanence of shape of the stiffener before, as well as after, it has been built into the shoe. The stiffener possesses the further advantage of making the heel seat of the completed shoe much firmer than has been possible heretofore, and produces a heel seat which is substantially flush with the heel, as shown in Fig. 10.

According to the preferred method of making the described heel counter, I first prepare a blank 14 of appropriate material, such for example as leather, whose curved edge will be skived in the customary manner, while its straight edge which is to form the inwardly-turned flange, instead of being skived in the ordinary manner, is reduced in thickness by removing from the piece of sheet material at 15 a portion of its thickness, thus forming, with the relatively thicker portion of the blank, an abrupt shoulder 16. This may be accomplished by the use of an appropriate channeling knife, or other suitable implement capable of splitting the leather from its bottom edge to a point 17, and then cutting inwardly from what is to be the outer face of the finished heel counter the proper distance from its edge to remove a piece from the outside, leaving the first cut or slit extending a slight distance beyond the shoulder 16, for a purpose which will presently appear.

If desired, the heel counter may be made without any reinforcement, but some manufacturers prefer to reinforce the heel counters, and in such cases, a reinforcement similar to the reinforcement 18 may be affixed to the inner face of the blank, and with a marginal portion 19 projecting beyond its edge. Preferably this reinforcement will be a textile material, such as canvas, cemented or otherwise appropriately affixed to the inner face of the blank. After the blank has been thus prepared, it is then shaped by

appropriate instrumentalities in a manner similar to the usual method of making heel counters, by bending the relatively thicker portion of the blank along its central portion into generally U-shaped form, and turning or wiping the reduced marginal portion inwardly toward the inside of the curve thus made, whereby the shoulder previously formed on the blank is caused to present an angular outer corner in the completed stiffener, as seen in Fig. 3. It should here be observed that the making of the cut or slit to a point somewhat beyond the shoulder, as already described, enables the reduced marginal portion to be bent and turned inwardly somewhat above the lower corner of the upstanding flange, so as to present a surface substantially flush with the lower edge of the upstanding flange. The inwardly turned flange may, of course, be crimped more or less in forming the same, but owing to its reduced thickness, the excessive crimping of the flanges, as heretofore formed, is avoided, and a flatter and less bulky flange is produced.

The inwardly turned flange may be slit or notched, if desired, as in the case of the toe box hereinafter described, but I find this to be unnecessary in the case of the heel counter, because in wiping the flange inwardly, no difficulty is experienced in making the same perfectly smooth without the excessive plaiting which characterizes heel counters as heretofore made.

Referring now to Fig. 10, wherein I have shown in vertical cross section the heel portion of a shoe, it will be observed that the reduced flexible flange produces a hinge-like connection between the heel seat and the upper of the shoe, and permits a degree of flexibility impossible with the use of heel counters as heretofore employed, as well as preserving a straight flush effect of the heel seat and preventing permanent distortion.

Referring now to Figs. 4, 5 and 6, I have there shown a toe box 20, embodying my invention, the same being provided with an inwardly turned flange 21, formed according to the described method, and differing therefrom only in that the flange at the toe portion of the box is preferably provided with a plurality of slits or notches 22, to prevent the flange from bunching as it is wiped inwardly at the round of the toe. If desired, these slits may be omitted, especially in cases where the toe of the completed shoe is so wide that it will be found to be unnecessary. The invention as applied to the toe box possesses all the advantages described in connection with the heel counter, including the angular outer corner, the flexibility of the inwardly turned flange, and the freedom from cracking at the corner, as

well as the flush appearance of the completed shoe.

While I have herein shown and described two specific forms or embodiments of my invention for illustrative purposes, and have disclosed and discussed in detail the construction and arrangement incidental to two specific applications thereof, it is to be understood that the invention is limited neither to the mere details or relative arrangement of parts, nor to the specific embodiments herein shown, but that extensive deviations from the illustrated forms or embodiments of the invention may be made, without departing from the principles thereof.

Having thus described my invention, what I claim and desire by Letters Patent to procure is:

1. As a new article of manufacture, a stiffener of fibrous material for boots and shoes having an upstanding flange, and an integral inwardly turned flange having a generally U-shaped inner edge, said flanges presenting at their juncture an abrupt change in thickness, said inwardly turned flange being substantially thinner adjacent said juncture than said upstanding flange, and said upstanding flange being substantially uniform in thickness from a point adjacent said juncture a substantial distance toward its opposite marginal portion. 95

2. As a new article of manufacture, a stiffener of fibrous material for boots and shoes having an upstanding flange and an integral inwardly turned marginal flange which, as compared with said upstanding flange is relatively thin and has substantially parallel inner and outer surfaces up to a point substantially in line with the inner surface of said upstanding flange, said marginal flange having a generally U-shaped inner edge, and said flanges presenting adjacent their juncture two outer surfaces substantially at right angles to each other. 100

3. As a new article of manufacture, a stiffener for boots and shoes having an upstanding flange and a relatively thin integral flange which is bent and turned inwardly at a point somewhat above the lower corner of the upstanding flange and has its lower surface substantially flush with an angular outer corner formed by the lower edge of the upstanding flange and the outer face of the latter. 115

In testimony whereof, I have signed my name to this specification, in the presence of two subscribing witnesses.

GEORGE E. ROLLINS.
